Hiram Shew

UNITED STATES PATENT OFFICE.

LAWRENCE L. NEEBE, OF WOODBURY, NEW JERSEY.

LOCOMOTIVE.

Application filed August 11, 1926. Serial No. 128,696.

My invention relates to certain improvements in the construction of the smoke-box end of a locomotive boiler and to the cylinder structure.

5 The invention is particularly adapted to locomotives of the three-cylinder type.

One object of the invention is to so construct the smoke-box end of the boiler as to allow the central cylinder of the three-10 cylinder saddle to project a considerable distance within the circumferential line of the smoke-box end of the boiler.

A further object of the invention is to so design the cylinder structure that the saddle is separated by the central cylinder of the structure, and supports the locomotive boiler on each side of the centre.

In the accompanying drawings:

Fig. 1 is a transverse sectional view on the line 1—1, Fig. 2, illustrating my improvements in locomotives;

Fig. 2 is a longitudinal sectional view on the line 2—2, Fig. 1; and

Fig. 3 is a detached perspective view of 25 the plate closing the opening in the bottom of the smoke-box of the boiler.

1 is the boiler of the usual type, having a smoke-box 2. 17 is the front tube-sheet. The bottom of the smoke-box section of the 30 boiler is cut away at *a*, and a segmental reinforcing plate 3 is secured in position within the smoke-box as clearly shown in the drawings.

The opening *a* is of sufficient size to allow 35 the central cylinder section 4 of the cylinder casting 5 to extend within the circumferential line of the smoke-box, and the portion 6 of the casting, containing an exhaust passage 7, terminates within the smoke-box 40 and supports the ordinary nozzle structure (not shown).

In order to close the opening in the bottom of the smoke-box, a shaped plate 8, such as shown in Fig. 3, is mounted within 45 the smoke-box and riveted or otherwise fastened thereto. In the present instance, the plate has a flange 9, and rivets pass through this flange into the body of the smoke-box casing. Other fastening means may be resorted to without departing from the essential features of the invention. The plate 8 is also secured to the extension 6 of the cylinder casting by bolts 11.

The cylinder structure 5 in the present instance is made in one piece, and formed in

this structure are the two side cylinders 12 and the central cylinder 4. Also formed in the casting are the valve-chests 13 for the two side cylinders and the valve-chest 14 for the central cylinder. The curved saddle 60 portions 15 are located on each side of the central cylinder and are bolted or otherwise secured to the boiler structure. The cylinder structure rests upon the side frames 16 and is secured thereto in the ordinary manner.

By this invention the diameter of the boiler can be increased and the height of the cylinder structure can also be materially increased without extending beyond the clearance line of the locomotive.

I claim:

1. The combination in a locomotive, of a cylinder structure having a central cylinder; a boiler having a smoke box section; an opening in the smoke box section to allow the central cylinder of the cylinder structure to extend within the circumferential line of the boiler; exhaust passages terminating within the smoke box; and a shaped 75 plate extending over the cylinder structure and perforated for the passage of that portion of the structure through which the exhaust passages extend, said plate being mounted within the smoke box and secured 80 to the boiler and to the cylinder casting.

2. The combination in a cylinder casting having side cylinders and a central cylinder, the casting having an exhaust passage extending above the central cylinder; a locomotive boiler having a smoke box at one 90 end; an opening in the bottom of the smoke box for the central cylinder structure; and a plate extending over the cylinder structure, said plate having an opening for the 95 passage of that portion of the cylinder structure containing the exhaust passage, said plate being flanged at each end and each side and secured to the boiler and to the cylinder structure.

3. The combination of a cylinder structure having a central cylinder and segmental side saddles; a boiler having a smoke-box section located above the cylinder structure, the lower portion of the smoke-box 105 having a reinforcing plate; an opening in the plate and in the bottom of the smoke-box section of the boiler; and a shaped plate closing said opening and having a central opening therein through which extends that 110

portion of the saddle structure to which an exhaust nozzle is attached.

4. The combination in a locomotive, of a cylinder structure having a central cylinder; a boiler having a smoke-box section, said section having an opening at the bottom to allow the central cylinder of the cylinder structure to extend within the circumferential line of the boiler; a reinforcing plate secured to the lower portion of the smoke-

box and having an opening therein; a shaped plate closing said opening, said plate having a flange; means for securing the flange to the boiler structure, the plate having an opening for the portion of the cylinder structure; and means for securing the plate to said structure, the cylinder structure having segmental saddles supporting the boiler. 13

LAWRENCE L. NEEBE.
